UNITED STATES PATENT OFFICE.

CHARLES J. EMERSON, OF OMAHA, NEBRASKA.

DENTAL MATRIX-RETAINER.

1,151,252.

Specification of Letters Patent. Patented Aug. 24, 1915.

Application filed October 17, 1914. Serial No. 867,111.

To all whom it may concern:

Be it known that I, CHARLES J. EMERSON, a citizen of the United States, residing in Omaha, in the county of Douglas and State 5 of Nebraska, have invented certain new and useful Improvements in Dental Matrix-Retainers, and have described the same in the following specification, illustrated by the accompanying drawings.

10 My invention relates to that class of retainers which have jaws and are used by dentists in connection with band matrices for the purpose of holding those matrices to the teeth while the latter are being filled. 15 Such a matrix, it will be understood, comprises a thin strip of easily flexible and practically inelastic metal, encircling or partly encircling a tooth in the human mouth. It is applied with recognized advantage in case 20 the cavity to be filled is located on the proximal surface of an upper or lower front tooth from which a portion of the lingual surface has been lost.

It is the object of the invention to adapt 25 a retainer of the specified class to grip by and between its jaws immediately, in each instance, a single tooth, to the exclusion of all others, and hold the matrix to that tooth; to avoid thereby the production of stresses 30 tending to move the teeth relatively to each other; to prevent the discomforts that commonly result from such stresses; and incidentally to simplify the construction of the retainer and render the appliance conveniently compact, and easy to be applied and 35 adjusted. To accomplish this object I incorporate in my improved retainer, as parts thereof, a pair of coacting hinged jaws which are adapted to engage respectively the 40 labial and the palatal or lingual surfaces of the tooth, means for adjustably closing and releasing the jaws, and a setscrew for engagement with the matrix.

In the accompanying drawings, illustrating 45 the best manner in which I have contemplated applying the principles of my invention, Figure 1 is a side elevation of a retainer which is constructed in accordance with these principles and operatively applied to a tooth and matrix which are shown in section. Fig. 2 is a front elevation of the same matrix and retainer, applied to a defective tooth standing between other teeth. Fig. 3 is a detail, being a plan of the flat 50 matrix blank before bending to fit the tooth. Fig. 4 is a perspective view showing a

matrix formed against one tooth, and having its band wrapped around another tooth. Fig. 5 is a perspective view of the complete retainer alone.

In the illustrated specimen of the invention the jaws are denoted by the numerals 1 and 2 respectively. They are hinged together at one end by the pivotal pin 3, are provided with inwardly directed 60 terminal teeth, or points, 4 and 5, respectively, and are radially of unequal length. They are connected by the transverse arm 6, which projects from the longer and bent jaw 1, spans the space between the jaws, extends 65 freely through a slot 12 in the shorter jaw, and is terminally provided with a screw thread and with the thumb-nut 7 for drawing the jaws together. The pointed screw 8, having a knurled head, works in a screw- 70 hole through the jaw 1 toward and from the jaw 2. This screw and the screw arm 6, as well as both of the described jaws, are disposed with their longitudinal axes in a single plane normal to the axis of the pin 3. 75

The matrix-forming strip, shown flat in Fig. 3, may advantageously be stamped from a thin sheet of German silver. Operatively the dentist bends or wraps this strip against or around an affected tooth 9 in the desired 80 form of the matrix 11', encircling the tooth more or less completely as may be required. Then he applies the jaws like external calipers, with the points 4 and 5 at the margins of the gums 10, as shown in Fig. 1; and 85 clamps the jaws immovably to the tooth between them by turning the nut 7. Then by turning the screw 8, and without disturbing the grip or position of the jaws 1 and 2 upon the tooth, he advances the screw point 90 against the side of the matrix or retracts that point, as occasion may require; by the advance he compresses a portion of the matrix between the screw and the tooth, and thereby plastically shapes the matrix to 95 the contiguous tooth surface; by the advance he likewise secures the matrix to its seat upon the tooth with greater or less firmness of pressure at different times, according to the requirements of the work; by the retraction of the screw he relaxes the pressure of the matrix upon the tooth, for the purpose of exposing the margin of the tooth cavity, or for other purposes, as may be desired. In this way the above stated object of the invention is accomplished in all its branches. 100 105 110

I claim—

1. A dental matrix retainer of the specified class, comprising a pair of tooth-holding jaws hinged together at one end, a transverse arm projecting from one of the jaws and working through a slot in the other jaw, a nut on the outer end of the arm, and a screw carried by one of the jaws and placed diagonally with its tip adapted to impinge upon the matrix on the tooth.
- 10 2. A dental matrix retainer of the specified class, comprising a pair of coacting hinged jaws adapted to engage opposing surfaces of the tooth which is to be filled, means for operating the jaws to clamp that tooth between them, and a screw working in one of the jaws, and positioned so as to form between the prolonged axis of the screw and the longitudinal axis of the tooth an acute angle on that side of the screw which is nearest the point of the tooth.
- 15 3. Dental apparatus of the kind described, comprising a band matrix for a tooth, a pair of hinged jaws for holding the tooth between them, and a screw working through one of the jaws at a distance from the pivotal axis of the hinge, and adapted to engage at a greater distance from that axis a matrix on the tooth so held.

In testimony whereof I subscribe this specification in the presence of two witnesses.

CHARLES J. EMERSON.
